UNITED STATES PATENT OFFICE.

GEORGE L. HARVEY, OF EVANSTON, ILLINOIS, ASSIGNOR TO THE ACME GAS COMPANY, OF CHICAGO, ILLINOIS, A CORPORATION OF ILLINOIS.

CARBURETER.

SPECIFICATION forming part of Letters Patent No. 716,227, dated December 16, 1902.

Application filed December 7, 1901, Serial No. 35,072. (No model.)

To all whom it may concern:

Be it known that I, GEORGE L. HARVEY, a resident of Evanston, in the county of Cook and State of Illinois, have invented certain new and useful Improvements in Gas-Making Apparatus, of which the following is a specification.

This invention relates to improvements in gas-making apparatus, and refers more specifically to apparatus of that type adapted to produce gas from hydrocarbons by passing air therethrough under pressure.

Among the salient objects of the present invention are to provide a construction in which the flow of oil from one to another of a series of closed carbureting-chambers is unaffected substantially by variations in air or gas pressure in different chambers of the series and wherein a plurality of such series are arranged in multiple, to provide interconnections between such multiple series whereby the different series may operate uniformly and, if desired, independently of each other without rearranging the pipe connections, to provide improvements in the detail of construction and arrangement whereby the flow of both gas-forming elements is efficiently regulated and controlled, to provide, in conjunction with gas-making apparatus of the general type referred to, a series of storage and circulating reservoirs wherein the hydrocarbon-supply is kept, modified in temperature, mixed, and stored, to provide improved connections between the several reservoirs and between the latter and the generating system, and in general to provide an improved system of apparatus of the character referred to.

To these ends the invention consists in the matters hereinafter described, and more particularly pointed out in the appended claims, and will be readily understood from the following description, reference being had to the accompanying drawings, in which—

Figure 1 is a plan view of two series of carbureters and connections of a preferred embodiment of my invention. Fig. 2 is a side elevation of the apparatus shown in Fig. 1. Fig. 3 is a vertical sectional view of a series of reservoirs and the pipe connections thereof. Fig. 4 is a vertical transverse section of

the apparatus, taken on the line 4 4 of Fig. 2, looking in the direction of the arrow.

Referring to the drawings, 1, 2, 3 and 1', 2', and 3' respectively designate two series 55 of carbureters conveniently arranged in parallel rows and connected, as hereinafter described, so that the gas-making elements may be circulated through the several series progressively.

4 and 4' designate pressure-equalizing air-chambers, respectively connected with the two series of generators, each of said equalizing-chambers being provided with an inlet-pipe, as 5 and 5', arranged to lead in through 65 its upper end and preferably discharging at a point near the bottom thereof, as indicated in dotted lines in Fig. 2. The two supply-pipes 5 and 5' communicate with opposite ends of a header 6, which is in turn supplied 70 through a common pipe 7, communicating with any suitable source of air under pressure—as, for instance, with an ordinary pressure-blower. Each of the pipes 5 and 5' is provided with suitable valve or turn-cock, as 75 8 and 8', whereby the flow of air therethrough may be shut off at will. With the upper end of each of the equalizing-chambers 4 communicates a pipe, as 9 and 9', the intaking end of which is preferably located near the upper 80 end of its chamber, and these pipes lead in through the top of the first ones of the respective series of carbureters and extend downwardly therein to points near the bottom walls, so as to discharge below the liquid- 85 levels therein, as will hereinafter appear. A similar pipe, as 10 and 10', leads out from the upper part of the first carbureter of the series and discharges within and below the liquid-levels of the next of the series, and similar pipes, as 11 and 11', are provided throughout the entire series. From the last carbureter of each series, as 3 and 3', outlet-pipes, as 12 and 12', extend to and communicate with a header 13, and with this header as 95 many take-off pipes may be connected as may be desired, one only, 14, being shown in the present instance.

In practice it is found necessary to at times modify the temperature of the air circulated 100 through the carbureters to form gas, and I therefore provide in each of the equalizing-

chambers 4 and 4' a heating-coil, (designated 15 and 15', respectively,) which heating-coil may be supplied from any suitable source of heat—as, for example, through a steam-pipe 16, arranged to extend vertically above the upper ends of the equalizing-chambers and provided with downward extensions, as 17 and 18, which respectively communicate with one end of each coil. The opposite ends of the coils are shown as extending out through the sides of the equalizing-chambers, as indicated at 19 and 20, and discharging into the outer air. Suitable valves 21 and 22 are provided to control the flow of steam or other heating fluid through the respective coils, so that the temperature in the equalizing-chambers may be regulated independently of each other.

Describing now the system of circulating the hydrocarbon through the carbureters, which hydrocarbon may and usually will be crude petroleum or a low-grade distillate, 23 designates as a whole a suitable pump, shown in the present instance as a steam-pump, supplied with steam through a pipe 24, connected with the steam-pipe 16, hereinbefore referred to. With the receiving side of the pump-cylinder 25 communicates a supply-pipe 26, the opposite end of which communicates with a source of oil-supply, hereinafter fully described. From the opposite side of said cylinder leads out a pipe 27, which is provided with two branches, as 28 and 28', respectively arranged to extend alongside of the two series of carbureters and conveniently on a level some distance above the lower ends thereof, as best indicated in Fig. 2. From these branch pipes 28 and 28' stub branches, as 29, 30, 31 and 29', 30', and 31', severally controlled by valves 32, lead into each of the several carbureters, as clearly indicated in Fig. 1.

Outlet-pipes for the hydrocarbon are also provided for each of the carbureters of the two series, preferably arranged as follows: From the first carbureter of each series, preferably at a point diametrically opposite its inlet-pipe 29 or 29', lead out a plurality of stub-pipe connections at different levels, as indicated at 33, 34, and 35 and 33', 34', and 35', which several stub-pipes communicate with a single stand-pipe or downtake 36 and 36', respectively, which in turn communicate with a horizontal pipe, as 37 and 37', leading to and communicating with the next carbureter of the series, preferably at a point on a level with the pipe 37 or 37'. These connections are duplicated or repeated throughout the series of generators, so that outlets are provided from each carbureter of a series at three different levels which communicate with the next carbureter of the series through a common connecting-pipe discharging into the latter carbureter at a level below any of the outlets of the preceding carbureter. Inasmuch as the pipes 37 and 37' connecting the several carbureters of the two series are desirably ar-

ranged on the same level they are deflected between their ends, so as not to interfere with each other, as best indicated in Fig. 1, it being understood that each pipe 37 or 37' has no connection with the succeeding pipe 37 or 37' except through the carbureter. From the last carbureter of the series a similar outlet-pipe, as 38 and 38', leads on and connects with a header-pipe 39 common to both series. With the header-pipe 39 communicates an outlet-pipe 40, which leads to a trap 41, with which communicates an outlet-pipe 42, which leads to a system of circulating-reservoirs best shown in Fig. 3 and now to be described. Referring to said Fig. 3, 44, 45, and 46 designate a series of reservoirs or tanks desirably arranged one above the other, the pipe 42 being continued to extend vertically alongside of each of said three reservoirs. From the pipe 42 branch pipes, as 47, 48, and 49, lead to and communicate with the upper part of each reservoir, these pipes being severally controlled by suitable turn-cocks 50, whereby the hydrocarbon may be admitted to either of the reservoirs or shut off at will. Each of the reservoirs is also provided at a point near its bottom with an outlet-pipe, as 51, 52, and 53, which several outlet-pipes communicate with a common riser 54, an extension of which forms the supply-pipe 26, which communicates with the circulating-pump 23. The several outlet-pipes 51, 52, and 53 are likewise provided with controlling-valves 55, whereby they may be independently shut off.

It will be seen from the foregoing that a complete circulation is provided for the hydrocarbon, extending from the circulating-pump through each series of carbureters to the header 39, thence through the trap 41 to the pipe 42 and to any one or all of the several tanks, and from the latter back to the circulating-pump through the pipes 54 and 26. Means are also provided for short-circuiting the series of tanks, so that the hydrocarbon may at will be circulated from the pipe 42 directly across to the return-pipe 54, such means comprising in present instance a cross connecting-pipe 56, extending between the pipes 42 and 54 at a point above the uppermost reservoir. The pipe 56 is provided with a valve 57, which may be closed to prevent the short circulation at will.

In order that a uniform pressure may obtain within the several reservoirs, the upper portions thereof are arranged to communicate with each other, each of said reservoirs being to this end provided with a communicating pipe, as 60, 61, and 62, which several pipes communicate with a stand-pipe 63. The several pipes 60, 61, and 62 are also provided with suitable valves 64. The stand-pipe 63, with the connecting-pipes 60, 61, and 62 communicating therewith, also enables the system of tanks to be utilized for distilling off the hydrocarbons of light specific gravity from one tank and condensing the distillate in another of the series, as will hereinafter

5 appear. Each of the several tanks is provided with a filling-inlet, each being conveniently and as shown herein provided at its upper side with a short pipe of relatively large diameter 65, provided with a controlling-cock 66.

In the practical use of apparatus of this character it is found that a certain amount of residue will be left after all the gas has 10 been obtained therefrom which is practicable, and the major portion of this residue will obviously collect at the bottoms of the several reservoirs. Means are therefore provided for withdrawing any portion of the 15 contents of the reservoirs at will. To this end each reservoir is provided with an outlet-pipe, as 67, 68, and 69, which several outlet-pipes communicate with a common discharge-pipe 70, which may lead to any suitable point 20 of discharge. These several pipes 67, 68, 69, and 70 are also provided with suitable controlling-valves 71 and 72.

In the carrying out of the process of generating gas from hydrocarbon, especially from 25 crude petroleum and the lower distillates, I have found that the generation of the gas is accompanied by a substantial lowering of temperature of the liquid and that the generation of gas is retarded by lowering of the 30 temperature of the liquid below a certain point and facilitated by maintaining a certain degree of heat. I therefore provide means for re-heating the supply of hydrocarbon being circulated through the system, and to this end I 35 arrange within each of the several reservoirs a heating-coil, as 73, 74, and 75, which heating-coils are arranged to communicate with any suitable source of steam or other heating-fluid supply. A heating-coil is provided 40 for each of the reservoirs in order that I may circulate the hydrocarbon through any one of the same, and material advantage will be obtained thereby, as will hereinafter appear. Means are also provided for draining the 45 several carbureters of the two series, and to this end I provide each carbureter with an outlet-pipe, as 76, located near the bottom thereof and conveniently upon the same side as the several overflow-pipes. These several outlet-pipes 50 76 are arranged to communicate with risers 77, 78, and 79 and 77', 78', and 79', which in turn discharge into a common drain-pipe 80, said risers being shown as conveniently forming extensions of the several pipes 36 and 36'. The common drain-pipe 80 extends to and communicates with the end of the header 39, thus communicating 55 with the reservoirs in the manner hereinbefore described, and in order that each carbureter may be drained independently of the other the several drain-pipes 76 are provided with controlling-cocks 81. At the conjunction of the risers 77, 78, and 79 and 77', 78', and 79' with the several pipes 36 and 36' are 60 located turn-cocks 82, which are normally closed, but may be open for a purpose hereinafter described. In this connection also it

may be explained that any one of the series of carbureters may be cut out of circuit by opening the drain-pipe 76 thereof, so as to 70 let the oil out of the carbureter and closing its inlet-pipe, which communicates with the distributing-pipes 29 or 29'. In case it be desired to cut out of circuit one of the intermediate carbureters—as, for example, No. 2—75 this may be accomplished by draining that carbureter and shutting off its supply, as hereinbefore described, and then opening the cocks 82 of the two risers 77 and 79 at each side thereof, so that the oil will circulate from 80 the first carbureter through the drain-pipe 80 past the intermediate carbureter and into the one beyond through the riser 79. This method of cutting out one or more of the carbureters is, however, not desirable. 85

In practice it is found desirable to pass the carbureted air or gas through a filtering medium in the several carbureters, this filtering medium serving both to prevent the too rapid or free flow of the air from one carbureter to 90 the other and also serving to prevent the carrying over of oil from one to the other in the form of spray. Accordingly one or more of the carbureters, preferably each one of the series, is provided with a filling of loose porous material, through which the carbureted air or gas may pass readily—such, for example, as granulated stone, coke, or the like, as indicated at 83 and 84 in Fig. 2. In the instance shown the filtering material is divided 100 into two bodies and is supported in position by means of perforated diaphragm or partition plates 85, secured at suitable intervals apart at points intermediate the height of the carbureter. 105

Describing next the circulation of the air through the series of carbureters, assuming that the main inlet-pipe 7 is connected with any suitable source of supply of air under pressure, the air entering the header 6 passes 110 into the equalizing-chambers 44' and is there heated by contact with the heating-coil 15, through which steam or other suitable heating fluid is circulated. From the equalizing-chamber the air passes out through the pipe 115 9 to the first carbureter of the series, the end of said pipe 9 being submerged below the liquid-level therein. The pressure of the air forces back the liquid in the pipe and escapes, rising upward through the body of the 120 liquid into the space above the liquid, becoming to a certain extent charged with the gas by being thus passed through the body of the oil. From the first carbureter the air passes on into the next and through the body of oil 125 contained therein, and so on throughout the series, being finally taken off from the last carbureter of the series through the outlet-pipe 12, which communicates with the header 13. The circulation through each series is 130 identical, and inasmuch as both series of carbureters discharge into the header 13 the gas taken off through the outlet-pipe 14, communicating with said header, will be of uniform

quality, notwithstanding there may be slight differences in the quality of gas produced by the different series of carbureters. If preferred, however, the gas may of course be led off from each series separately, and this may be advisable where it is desirable to produce different qualities of gas from the same apparatus. This latter result may be attained by simply passing the air through a greater or less number of carbureters.

Describing now more particularly the operation of the series of reservoirs in conjunction with the gas-generating apparatus the several tanks may be conveniently utilized for holding different qualities of hydrocarbon. For example, assuming that a quality of hydrocarbon is used which contains a certain percentage of distillate which is too light to be used advantageously in the gas-generating apparatus the hydrocarbon may be charged into one of the reservoirs—for example, the uppermost one—and heated by means of the heating-coil 73 thereof to a sufficient temperature to cause the lighter distillate to pass off as vapor and through the pipes 60 and 63 into one of the lower reservoirs, where it may be condensed. When the hydrocarbon in the uppermost reservoir has been reduced to a proper quality, the distillation may be arrested and this supply of hydrocarbon used for generating gas, while the same process of distilling may be carried on with the two remaining reservoirs, thereby insuring a ready supply at all times without interruption of the gas-making process. Ordinarily, however, the several reservoirs will not be used for distilling as described, but will be used alternatively to supply the oil needed for circulation through the carbureters, the two upper reservoirs being used alternatively and the lowermost reservoir being employed to receive the residuum which is too heavy and cannot be converted into gas.

The provision of the heating-coils in each of the reservoirs enables the hydrocarbon to be kept at the temperature most conducive to the generation of gas, and I have found in practice a large percentage of the oil can be converted into gas when the oil is kept warm. The operation of filling the several tanks is obvious, and the manipulation of the connections so as to throw either one in circuit with the carbureter system and also the manipulation of the connections for draining or discharging the several tanks have hereinbefore been fully described and need not be repeated.

The operation of the apparatus, constructed as hereinbefore described, may be as follows: Assuming that a suitable supply of hydrocarbon is placed in one or more of the reservoirs, the valves are so set as to connect the circulating-pipes 42 and 54 therewith and the pump 23 started and continued in operation until the several carbureters have been charged up to their normal working levels and the oil begins to overflow back into the reservoir. Oil pumped in through the pipe

27 and branches 28 and 28' thereof enters the first pair of carbureters 1 and 1' through the stub-pipes 29 and 29' and rises to the level of the latter, it being understood that the inlets through the pipes 30 30' and 31 and 31' will ordinarily be closed.

Inasmuch as the circulation through each series of carbureters is identical a description of the circulation through but one series will be given, it being understood that the circulation through the other series will be the same. From the carbureter 1 the oil passes out from that one of the outlet-pipes 34 or 35 which is open, usually through the former, and descends through the pipe 36 to the pipe 37, leading to the next carbureter of the series. In this carbureter the oil again rises to the overflow-level, passing out through its pipe 34 or 35 and through the next communicating-pipe 37 to the last carbureter, as before. From the last carbureter of the series the oil overflows into the pipe 38 and thence to the header 39, entering the trap 41 through the pipe 40 and passing on from the trap through pipe 42 to the reservoir, which for illustration may be considered as being the uppermost reservoir 44, thus completing the circuit of circulation. Obviously the depth of oil in the different carbureters may be determined by properly setting the cocks controlling the pipes 34 and 35, it being understood that if the two latter pipes are closed the oil will be compelled to pass out from the uppermost pipe 33, which is open at all times. It will be obvious also that this last pipe affords a safety overflow which would prevent flooding of the carbureter in case the branch pipe which serves to determine the normal level should become clogged.

It will be understood from the foregoing description that a system embodying my invention may be made of a capacity to meet almost any possible demand, since the number of series of carbureters connected in multiple in manner described may be multiplied to any reasonable extent. Furthermore, by the system of connections and arrangement shown it is possible to disconnect or cut out not only any given carbureter, but any entire series of carbureters, without mechanically disconnecting the units. The system constructed and arranged as described is admirably adapted for installation below ground, and especially the supply or reservoir part of the system, for the reason that there are no moving or operative parts except the turn-cocks, and those may be readily connected up so as to be operated from aboveground, and the system may therefore be operated indefinitely without inspection. The possibility of locating the hydrocarbon-supply underground is a feature the importance of which need not be dwelt upon.

The novel process of generating gas by the use of an apparatus wherein a constant circulation of the hydrocarbon is maintained and the air is passed successively through

bodies of liquid is made the subject of another application filed contemporaneously herewith, Serial No. 85,070, and is therefore not made the subject of claims herein.

5 I claim as my invention—

1. In a gas-making apparatus, the combination of a series of carbureters, a hydrocarbon-supply pipe arranged to extend along the series of carbureters, and provided with a branch pipe communicating with each, controlling-cocks for the several branch inlet, an overflow outlet-pipe leading out of each carbureter and communicating with the next of the series, except the last, the outlet of which communicates with a return-pipe, a drain-pipe communicating with each carbureter, a common return-pipe with which both the drain-pipe and the outlet-pipe of the last of the series of generators communicates, 20 and means for circulating the hydrocarbon through the series of carbureters.

2. In a gas-making apparatus, the combination of a series of carbureters, a hydrocarbon-supply pipe arranged to extend along the series of carbureters and provided with a branch pipe communicating with each, controlling-cocks for several branch inlet-pipes, an overflow-pipe leading out of each carbureter and communicating with the next of the series, except the last, an overflow-pipe for the latter, a common return-pipe with which said latter overflow-pipe communicates, a drain-pipe branch communicating with each carbureter, a drain-pipe common to said several branches and arranged to communicate with the common return-pipe, and controlling-cocks for each of said branch drain-pipes, substantially as described.

3. In a gas-making apparatus, the combination of a series of carbureters, a hydrocarbon-supply pipe arranged to extend along the series of carbureters, and provided with a branch pipe communicating with each, controlling-cocks for said several branch inlet-pipes, an overflow outlet-pipe leading out of each carbureter of the series, except the last, and communicating with the next in order, an outlet-pipe leading from the last of the series, a common return-pipe with which said last outlet-pipe communicates, a branch drain-pipe leading from the bottom of each carbureter, risers communicating with said several outlet and drain pipes of each carbureter, a common drain-pipe with which each 55 of said risers communicates, said drain-pipe likewise communicating with the common return-pipe, and controlling-cocks arranged to control the communications between the several carbureters and risers, and between the overflow outlet-pipes of the carbureters and risers, as and for the purpose set forth.

4. In a gas-making apparatus, the combination of a series of carbureters, a hydrocarbon-supply pipe arranged to discharge into the first carbureter of the series, a riser arranged adjacent to each carbureter, a plurality of outlet-pipes forming communication

between each carbureter and its riser at different levels, cocks arranged to control each of said outlets, except the uppermost, an overflow outlet-pipe extending from each riser to, and communicating with the carbureters of the next in order of the series, except the last, an overflow outlet-pipe extending from the latter to, and communicating with a common return-pipe, a series of drain-pipes, one for each carbureter communicating with said respective risers, a common drain-pipe with which the lower ends of the several risers communicate, cocks arranged to control said drain-pipes, said common drain-pipe being also arranged to communicate with said common return-pipe, and a pump operating to return the hydrocarbon from the common return-pipe to the supply pipe, substantially as described.

5. In a gas-making apparatus, the combination of a series of carbureters, a hydrocarbon-supply pipe arranged to discharge into the first carbureter of the series, a riser arranged adjacent to each carbureter, a plurality of outlet-pipes forming communication between each carbureter and its riser at different levels, cocks arranged to control each of said outlets, except the uppermost, an overflow outlet-pipe extending from each riser to, and communicating with the carbureter of the next in order of the series, except the last, an overflow outlet-pipe extending from the latter to, and communicating with a common return-pipe, a series of drain-pipes, one for each carbureter communicating with said respective risers, a common drain-pipe with which the lower ends of the several risers communicate, cocks arranged to control said drain-pipes, said common drain-pipe being also arranged to communicate with said common return-pipe, a reservoir into which said return-pipe discharges, and a pump, having its suction side in communication with its reservoir and its discharge side communicating with the discharge-pipe of the system, substantially as described.

6. In a gas-making apparatus, the combination of a plurality of series of carbureters, a common hydrocarbon-supply pipe, provided with branches arranged to communicate with the first carbureter of each series, an overflow outlet-pipe leading out of each carbureter and communicating with the next of its series, except as to the last carbureters of the said several series, overflow outlet-pipes for said several last carbureters, a common return-pipe with which the overflow-pipes of the last carbureters severally communicate, a series of gas-pipes for each series of carbureters receiving their supply from a common source of air or gas under pressure, each of said gas-pipes being arranged to discharge below the liquid-level of the carbureter into which it discharges, and a common main into which all of the outlet gas-pipes of the last carbureters of the several series discharge, as and for the purpose set forth.

7. In a gas-making apparatus, the combination of a plurality of series of carbureters, a common hydrocarbon - supply pipe provided with branches arranged to communicate with the first carbureter of each series, an overflow outlet-pipe leading out of each carbureter and communicating with the next of its series, except as to the last carbureters of the said several series, overflow outlet-pipes for said several last carbureters, a common return - pipe with which the overflow-pipes of the last carbureters severally communicate, a pump having its inlet side arranged to communicate with said return-pipe, and its discharge side communicating with said hydrocarbon-supply pipe, a series of gas-pipes for each series of carbureters receiving their supply from a common source of air or gas under pressure, each of said gas-pipes being arranged to discharge below the liquid-level of the carbureter into which it discharges, and a gas-outlet pipe leading from the last carbureter of each series.
8. In a gas-making apparatus the combination of a plurality of series of carbureters, a system of hydrocarbon supply and discharge pipes connecting said series in multiple with a common return-pipe, and a pump connected with said common return-pipe and with the supply-pipe of said hydrocarbon system whereby a circulation of hydrocarbon is maintained through the carbureters.
9. In a gas-making apparatus, the combination of a plurality of series of carbureters, a system of hydrocarbon supply and discharge pipes connecting said series in multiple with a common return-pipe, a pump connected with said common return-pipe and with the supply-pipe of said hydrocarbon system, and a system of gas-pipes having a common source of supply of air or gas under pressure, and likewise connecting said several series in multiple, whereby a circulation of hydrocarbon is maintained through the carbureters.
10. In a gas-making apparatus, the combination of a plurality of series of carbureters, a system of hydrocarbon supply and discharge pipes connecting said series in multiple with a common return-pipe, a pump connected with said common return-pipe and with the supply-pipe of said hydrocarbon system, and a system of gas-pipes having a com-

mon source of supply of air or gas under pressure, likewise connecting said several series in multiple, and means for initially heating said supply of air or gas. 55

11. In a gas-making apparatus, the combination of a plurality of series of carbureters, a system of hydrocarbon-supply pipes connecting said series in multiple with a common return-pipe, a pump connected with said common return-pipe and with the supply-pipe of said hydrocarbon system, and a system of gas-pipes having a common source of supply of air or gas under pressure, likewise connecting said several series in multiple, and means for heating the hydrocarbon-supply during one part of its circulation. 65

12. In combination with a series of carbureters, the hydrocarbon-supply-pipe system thereof and a common return-pipe, a plurality of reservoirs connected in parallel between the common return and supply pipes of said system, substantially as described. 70

13. In combination with a series of carbureters and the hydrocarbon-supply-pipe system thereof, a plurality of reservoirs arranged at different elevations and connected in parallel between the common return and supply pipes of said system, substantially as described. 75

14. In combination with a series of carbureters and the hydrocarbon-supply-pipe system thereof, a plurality of reservoirs arranged at different elevations and connected in parallel between the common return and supply pipes of said system, each of said reservoirs being provided with a heating-coil, substantially as described. 80

15. In combination with a series of carbureters and the hydrocarbon-supply-pipe system thereof, a plurality of reservoirs arranged at different elevations and connected in parallel between the common return and supply pipes of said system, each of said reservoirs being provided with a heating-coil, and a riser provided with branch pipes communicating with the upper part of each of the series of reservoirs, as and for the purpose set forth. 95
